(57) **CLAIM**

The ornamental design for a cross member for video and photographic apparatuses, as shown and described.

DESCRIPTION

FIG. 1 is a bottom plan view of the cross member of the present design;

FIG. 2 is a side view of the cross member of the present design;

FIG. 3 is a front elevational view of the cross member of the present design;

FIG. 4 is a view from the other side of the cross member of the present design;

FIG. 5 is a rear view of the cross member of the present design;

FIG. 6 is a perspective view of the cross member of the present design; and,

FIG. 7 is a top plan view of a cross member of the present design.

The portions of the Figures shown in phantom lines are not part of the claimed design and are for illustration only.
